[57] ABSTRACT

In an air compressor system for supplying compressed air to a receiving tank and being operated by an internal combustion engine including a carburetor; a control is provided for operating the carburetor throttle between idle and full speed positions in response to the pressure in the air receiving tank. The carburetor control includes a reciprocable pneumatic motor supplied with air from the receiving tank through a pilot valve. Additionally, the pilot valve controls the flow of air from the receiving tank to the air compression cylinders for purposes of unloading the latter at the same time the carburetor is moved to idle position when the air in the receiving tank reaches a predetermined amount. Air for unloading the compression cylinders is sequentially fed into the compression cylinders so that the load on the engine is gradual during loading and unloading of the compression cylinders. The air intake manifold for supplying the compression cylinders with air to be compressed is also connected to the carburetor to divert air to the carburetor to reduce the temperature of the air passing through the air compression cylinders during unloading and thereby reduce the temperature of the compressor valves during this stage. In one modification, the control system is further provided with a thermostatic valve which senses the temperature of the cooling water in the engine to detain the air compressing operation until the engine has become sufficiently warm as sensed by the temperature of the cooling water in the engine.

FIG. 4

AIR COMPRESSORS

OBJECTS OF INVENTION

The present invention generally relates to a gas compressing system and more specifically to a novel and improved system and method for controlling a gas compressor such as an air compressor particularly of the type driven by an internal combustion engine. The present invention also relates to a novel carburetor control and linkage.

One of the objects of the present invention is to provide a novel and improved control system for controlling the operation of a gas compressor such as an air compressor. Included herein is the provision of such a control system which is particularly suitable for air compressors driven by an internal combustion engine.

A further object of the present invention is to provide such a control system which will control the operation of a gas compressor in response to pressure in the receiving tank which is supplied with compressed gas by the compressor. Included herein is the provision of such a control system which eliminates conventional control systems and those of the prior art which operate in response to the speed of the engine that drives the compressor.

Another object of the present invention is to provide such a control system which gradually loads and unloads the gas compression cylinders of the compressor to reduce load and wear on the associated engine.

Yet another object of the present invention is to provide such a control system for a gas compressor which will permit operation of the gas compressor only after the associated engine reaches a predetermined warm temperature.

A still further object of the present invention is to provide a novel control for a carburetor including a novel linkage for operating the throttle lever of the carburetor, which control and linkage may be connected to a source of compressed air or other gas to operate the carburetor in response to gas pressure. Included herein is the provision of such a control and linkage which reduces wear on the carburetor throttle shaft while further reducing shocks imparted thereto when moved between idle and full speed positions. Further included herein is the provision of such a carburetor control and linkage which may be substituted in a conventional carburetor system employed with conventional air compressors.

SUMMARY OF THE INVENTION

The above and other objects are achieved in an air compressor system such as may include a block containing a plurality of air compression cylinders with conventional valves for controlling the supply and exhaust of air into and from the cylinders and conventional reciprocating pistons for compressing air in the cylinders. Additionally, the block contains a plurality of internal combustion cylinders equipped with reciprocating pistons for driving a crank shaft which in turn drives the air compression pistons in conventional manner. Air compressed in the air compression cylinders is fed to an air receiving tank which is equipped with an outlet nozzle for connection to a pneumatic device to power the same.

In accordance with the present invention, the carburetor for the internal combustion engine is operated in response to the pressure in the air receiving tank so that when the air in the latter reaches a predetermined pressure for example 100 psi, the carburetor will be moved to an idle speed position simultaneously with opening of the valves in the air compression cylinders to unload the same. This is achieved by connecting a reciprocable fluid motor such as an air cylinder to the lever mounted on the carburetor throttle shaft to rotate the same upon actuation of the fluid motor in response to air pressure from the air receiving tank. The fluid motor is provided with a return spring so that when the air pressure in the receiving tank falls to a predetermined amount for example 85 psi, the return spring will cause the throttle lever of the carburetor to rotate in the opposite direction into the full speed position at which time the air compressing operation will resume in the compression cylinders to restore the pressure in the air receiving tank.

The fluid motor is supplied with and exhausted of air through means of a pilot valve connected to the air receiving tank. The pilot valve also is connected to unloading pistons associated with the air compression cylinders to control the loading and unloading thereof. Thus when the pressure in the air receiving tank reaches a predetermined amount such as 100 psi, the pilot valve will open and admit air to the fluid motor to move the carburetor to the idle position while simultaneously providing air to the unloading pistons of the air compression cylinders to open the valves therein and vent the cylinders to atmosphere and to thereby unload the same and cease the compression of air.

Upon use of the compressed air from the receiving tank the pressure therein will of course drop, and when the pressure drops to a predetermined value say 85 psi the pilot valve will move to another position closing communication with the tank while venting the fluid motor and the unloading pistons to atmosphere whereupon the carburetor will move to the full speed position and air compression will resume in the air compression cylinders. To reduce the load on the engine, the unloading pistons are connected in series by one line to the pilot valve so that the compression cylinders are sequentially gradually loaded and unloaded.

The carburetor control is further provided with adjustable safety stops for determining the idling and full speed positions thereof of the carburetor. Additionally the stop which governs the idling speed is provided with a rubber bumper to absorb shocks when the carburetor throttle lever is moved to the idling position.

When the carburetor is in the idle position and the compression cylinders are unloaded and air is moving through the compression cylinders to atmosphere, the temperature of the air passing through the cylinders will increase the temperature of the valves in the air compression cylinders. This increased temperature if unchecked may cause damage to the valves. To overcome the latter, an air line is connected between the air intake manifold and the carburetor to divert some of the air away from the compression cylinders to the carburetor.

The system may be modified to add a thermostatic control valve which senses the temperature of the water in the cooling system of the engine and detains the air compressing operation until the temperature of

the cooling water reached a predetermined amount such as 140° F.

DRAWINGS

Other objects and advantages of the present invention will become apparent from the following more detailed description of the drawings in which:

FIG. 1 is a schematic view of an air compressor system embodying the present invention;

FIG. 2 is an elevational view of a carburetor control system included in the system of FIG. 1;

FIG. 3 is a plan view of a linkage which is a part of the carburetor control system of FIG. 2; and

FIG. 4 is a view similar to FIG. 1 but illustrating a modified system further in accordance with the present invention.

DETAILED DESCRIPTION

Referring to the drawings in detail there is shown for illustrative purposes only in FIG. 1 a schematic of an air compressing system including a block 10 having four air compression cylinders 12 and four internal combustion cylinders 14. The aforementioned arrangement may be made by converting a standard V-8 internal combustion engine such as for example disclosed in U.S. Pat. No. 1,992,400 to T.G. Smith owned by the assignee of the subject application; the disclosure of said patent being incorporated by reference herein. Compression of air in air cylinders 12 may be by conventional reciprocating pistons and compressor valves (not shown) such as of the type shown in the aforementioned U.S. Pat. No. 1,992,400 and therefore need not be described in any detail. Additionally the air compression cylinders 12 and their associated parts may conform to that disclosed in U.S. Pat. application Ser. No. 256,604 filed May 24, 1972 entitled SEAL ASSEMBLY FOR AIR COMPRESSOR VALVE, assigned to Gordon Smith & Co., Inc., the assignee of the subject application and whose disclosure is hereby incorporated by reference herein. These parts also may conform to those included in the model 90 air compressor manufactured by Gordon Smith & Co., Inc. of Bowling Green Kentucky, the assignee of the subject application. The internal combustion cylinders 14 may also be any suitable conventional or other type such as may conform to that disclosed in the aforementioned U.S. Pat. No. 1,992,400 or incorporated in the model 90 air compressor manufactured by Gordon Smith & Co., Inc. The same applies with respect to other parts of the engine such as the battery and ignition system and cooling system etc. which although not shown may be conventional and are well known and therefore need no further description.

Returning now to FIG. 1, air is supplied to an air intake manifold 16 through an air filter 18 where it is led for example through the schematically illustrated lines 20 to the compression cylinders 12 to be compressed therein and later discharged to an air receiving tank 22 through an air discharge manifold 24 connected to air compression cylinders 12 such as schematically illustrated by lines 26. Fuel for combustion cylinders 14 is provided from a fuel tank (not shown) through a carburetor 30 having a carburetor or throttle shaft 32 on which is fixed a throttle lever 34 for purposes of rotatably oscillating the carburetor shaft 32. The carburetor is further shown as provided with a conventional choke shaft 36 connected to a choke cable 38 which form no

part of the present invention. It should further be understood that the internal parts of the carburetor not shown also form no part of the present invention as they may be conventional or otherwise insofar as the disclosure of the present invention is concerned.

When throttle lever 34 is in one position indicated by the line 40 in FIG. 2 the carburetor will be in the idle speed position which is used when the compression cylinders 12 are in an unloading mode during which time air is being brought into the air compression cylinders 12 through lines 20 and discharged therefrom to atmosphere with no air compression taking place. In the opposite position of throttle lever 34 shown by line 42, the carburetor will be in the full speed position which is employed to operate the pistons in the air compression cylinders 12 at the desired speed for compressing air. In this condition, the valves in air compression cylinders 12 will be loaded and the air compression operation will take place to provide compressed air to air receiving tank 22 via air discharge manifold 24. During this air compression mode, the valves associated with the air compression cylinders 12 are operating to emit air into the air compression cylinders for compression and to discharge compressed air into discharge manifold 24. When the pressure in the air receiving tank 22 reaches a certain predetermined amount such as 100 psi, the valves associated with air compression cylinders 12 are unloaded so that air fed into compression cylinders 12 through lines 20 is not compressed but rather is vented to atmosphere. This occurs during the idling position of the carburetor. Movement of the air compressor valves for unloading air compression cylinders 12 is achieved through an unloading piston associated with each of the air compression cylinders, the unloading pistons not being schematically shown at 25. The unloading pistons are operated in response to fluid pressure preferably air pressure in accordance with the present invention as will be described below in greater detail. For a further detailed disclosure of the air compressor valves and the unloading pistons, reference may be made to the aforementioned copending U.S. Pat. application Ser. No. 256,604 filed May 24, 1972 entitled SEAL ASSEMBLY FOR AIR COMPRESSOR VALVE. It should be understood however that any other type of fluid operated unloading piston may be employed in carrying out the present invention.

In accordance with the present invention, the throttle lever 34 of the carburetor is moved between idle and full speed positions in response to the pressure in air receiving tank 22. In the shown embodiment, this is achieved by providing a fluid motor which may be a pneumatic motor 50 in the form of an air cylinder having a piston therein operated by air supplied from air receiving tank 22. Air cylinder 50 may be mounted in any suitable manner relative to the block 10 such as by the generally U-shaped bracket 52 which may be made from rigid material such as a suitable steel or alloy material. Referring to FIG. 2 bracket 52 includes two spaced upstanding arms 54 and 56 both having apertures therein; one receiving an adjustable stop in the form of a stud 58 having threads thereon received in complimentary threads in arm 56 and further including a lock nut 60 threaded on stud 58. The aperture in the other arm 54 is threaded to receive one end of air cylinder 50 and a lock nut 62 is provided therein to secure the air cylinder to arm 54. The piston shaft of pneumatic cylinder 50 is connected to an elongated rod 64

having threads on one end at 66 for receipt in a hexagonal coupling 68. The other end of coupling 68 has a ball and socket joint including a ball member 70 having a hexagonal portion 72 and a threaded stud portion 74 which is received in a sleeve 76 with a lock nut 78 received on the stud portion 74. As shown in FIG. 3, sleeve 76 is recessed at one side at the other end thereof and is connected to throttle lever 34 by means of a threaded stud 80 which passes through an aperture in throttle lever 34 and is secured relative thereto by lock nuts 82 and 84. Stud 80 is connected to sleeve 76 by a ball-socket joint at 86.

It will be seen that upon reciprocation of the piston of air cylinder 50 the motion will be transmitted to throttle lever 34 by sleeve 76 to oscillate throttle shaft 32. Movement of the linkage assembly 64, 68, 76 to the right as viewed in FIG. 2 will place the carburetor shaft 32 in position for idling, whereas movement to the left will place the carburetor shaft 32 in position for full speed operation. The idling position is determined by engagement of the forward end of sleeve 76 against stop 58 which will lessen the shock and wear on throttle shaft 32. To further reduce shock a rubber or other resilient bumper 90 is placed over the extremity of stop 58 as shown in FIG. 2. To adjust the idling position of the throttle lever 34, lock nut 60 in stop 58 is loosened away from bracket arm 56 and stud 58 is rotated to move it towards or away from sleeve 76 depending on whether the idling speed is desired to be increased or decreased.

The full speed position of the throttle shaft 32 is determined by the distance between the stud 80 and rod 64. By loosening lock nut 78, hexagonal portion 72 may be grasped by a tool and rotated to advance or retract stud portion 74 out of or into sleeve 76 to adjust the full speed of the carburetor. In addition a safety stop 94 is provided in the form of a screw mounted in the base of throttle lever 34 as shown in FIG. 2. A coil compression spring is provided between the head of screw 94 and the lever 34 to secure the screw against movement. At the base of the carburetor a pin (not shown) is provided in fixed position to engage screw 94 when the lever moves into the full speed position. This insures that the lever 34 cannot be moved beyond a certain full speed set by the operator. Movement of the linkage to the left as viewed in FIG. 2 to place the carburetor in the full speed mode is obtained by a return spring 98 in air cylinder 50 when the latter is exhausted of air as will be described below.

Referring to FIG. 1, air is fed to the pneumatic cylinder 50 to operate the same for moving the carburetor throttle lever 34 to the idling position through a pilot valve 100 connected to receive air from receiving tank 22 by line 102. The outlet 104 of the pilot valve is connected to T joint 106 for supplying air to pneumatic cylinder 50 via line 108 and also for supplying air to the unloading pistons of the air compression cylinders 12 through line 110. In accordance with another aspect of the present invention, the unloading pistons of the air compression cylinders receive their air from line 110 sequentially and gradually through lines 114, 116 and 118 so that the air compression cylinders 12 are gradually loaded and unloaded to reduce load on the engine. Lines 114, 116 and 118 may consist of one-eighth inch diameter tubing. Air passing to the unloading pistons of the air compression cylinders will first pass through the cylinder 12 shown in the left hand side of FIG. 1 and

then to the next adjacent cylinder and then to the next adjacent cylinder and then finally to the cylinder on the right hand side of FIG. 1. The unloading cylinders will also be sequentially and gradually exhausted to atmosphere through the vent 120 of the pilot valve.

Pilot valve 100 itself may have any suitable conventional construction including a condition responsive ball check valve 122 which will open when the pressure in air receiving tank 22 reaches a certain value such as 100 psi to permit air to flow from the air receiving tank through line 102 to pneumatic cylinder 50 through line 108 and simultaneously to the unloading pistons of the air compression cylinders through lines 110 and 114, 116 and 118. This will have the effect of moving carburetor throttle 34 to the idling position while causing the air compression cylinders 12 to unload whereby air fed into the air compression cylinders through lines 20 is vented to atmosphere and no compression takes place.

When the air in receiving tank 22 is used to operate a device by opening valve 130 the pressure in air receiving tank 22 falls to a certain value such as 85 psi, the check valve 122 in pilot valve 100 will close and the air vent 120 will be placed into communication with lines 108 and 110 whereby the air in pneumatic cylinder 50 and the unloading pistons will be vented to atmosphere through pilot valve 100 and vent 120. The spring 98 associated with pneumatic cylinder 50 will then cause the pneumatic cylinder piston shaft to move to the left (as viewed in FIG. 1) thereby causing carburetor throttle lever 34 to pivot counterclockwise into the full speed position wherein the air compression operation in the air compression cylinders 12 will resume and compressed air will be supplied to air receiving tank 22 through air discharge manifold 24.

As noted above, during the unloading cycle of the air compression cylinders 12, air is being fed from the air intake manifold 16 through lines 20 to compression cylinders 12 which can cause the temperature of the compressor valves associated with the air compression cylinders to increase to an unsafe degree causing damage to the air compressor valves. To reduce the temperature of the valves, a conduit 132 is placed between the air intake manifold 16 and carburetor 30 to supply the carburetor with a portion of the air from intake manifold 16. This will lessen the amount of hot air fed through the air compression cylinders 12 to thereby reduce the temperature of the compressor valves.

The control system of the present invention may be modified to add a thermostatic control valve to detain the air compressing operation until the temperature of the cooling water in the internal combustion engine has reached a desired degree for example 140° F. Referring to FIG. 4 a thermostatic control valve 140 may be mounted on the block or on the radiator 142 to sense the temperature of the cooling water 144 in the engine system.

Thermostatic control valve 140 may be any suitable or conventional type readily obtainable on the market such as includes two inlet ports 152 and 156 which may be alternatively placed in communication with an outlet port 146 by means of a spool valve member 143 having a plurality of spools 145 for controlling registration between ports 152, 156 and 146. Valve 140 further includes a temperature sensing element 139 in contact with the cooling water 144 in the engine system so as to actuate the spool member 143 in response to

the temperature of the cooling water 144. Port 152 is placed in communication with the air in receiving tank 22 by means of line 154 while port 156 is adapted to be placed into communication with receiving tank 22 through means of pilot valve 100 which is the same as that disclosed in FIG. 1 and described above. Outlet port 146 of valve is connected to unloading pistons 25 of air compression cylinders 12 by means of line 148, and connected to air cylinder 50 controlling the carburetor by means of line 150.

Upon initial starting of the engine, the cooling water 144 will be less than 140° F and the spool valve member 143 will be in position to open communication between ports 152 and 146. Air will thus be fed from receiving tank 22 through line 154 port 152, port 146 and line 148 to send air to the unloader pistons 25 associated with the air compression cylinders. However the pressure in receiving tank 22 at this time will not be sufficient to cause the unloading pistons 25 to move into an unloading position. Thus air compression in air cylinders 12 begins to take place at this initial phase. At this time pilot valve 100 will be closed since the pressure in air receiving tank will be less than that required to open up the ball check valve in pilot valve 100.

When the pressure in air receiving tank reaches a predetermined amount for example 40 psi this will be sufficient to actuate unloading pistons 25 associated with the air compression cylinders 12 and also to actuate fluid motor 50 to the right as viewed in FIG. 4 to place the carburetor in idling position. Thus no further air compression will take place in cylinders 12 as is desired since the engine at this time is not sufficiently warm. The engine will continue to idle with the compression valves unloaded until the temperature of the cooling water 144 of the engine reaches a predetermined amount 140° F as sensed by sensing element 139. When this occurs spool valve member 143 will be moved to close communication between ports 152 and port 146 and open communication between ports 146 and 156. At this point check valve 122 of pilot valve 100 will be in closed position such that pilot valve 100 will vent air from the thermostatic valve 140 to atmosphere through vent port 120. This will cause return spring 98 in fluid motor 50 to move the carburetor to full speed position while also permitting air compression to take place in cylinders 12. From this point on and as long as the temperature of the cooling water 144 of the engine remains at 140° F or above, the thermostatic control valve 140 will remain in position wherein line 158 is open to communication with lines 148 and 150. When the pressure in the receiving tank reaches the predetermined value for example 100 psi, the ball check valve in pilot valve 100 will open permitting air from receiving tank 22 to be conveyed through line 158 and lines 148 and 150 to unload the air compression cylinders 25 and to move the carburetor to the idling position as described above.

I claim:

1. In a gas compressor system including gas compressor means for compressing a gas such as air, a gas receiving chamber supplied with compressed gas from said compressor means, said compressor means including unloading means for preventing compression of gas, drive means including an internal combustion engine for driving said gas compressor means, and control means for moving said drive means to an idling position wherein it operates at a certain low speed and for mov-

ing said unloading means to prevent gas compression in response to a first predetermined pressure in said receiving tank, said control means further including means for moving said drive means to a full speed position and for simultaneously restoring said unloading means to permit compression of gas by said compressor means in response to a second predetermined pressure in said receiving tank lower than said first predetermined pressure, and wherein there is further included 10 temperature control means responsive to the temperature of said internal combustion engine for preventing gas compression until the temperature of said internal combustion engine has reached a predetermined degree upon start up of the engine and regardless of the pressure in said receiving tank.

2. The system defined in claim 1 wherein said drive means includes a carburetor and a fluid actuated motor for operating the carburetor in response to pressure in said receiving tank, and wherein said first control 20 means includes valve means for controlling the flow between said receiving tank and said fluid actuated motor, and wherein said temperature control means includes a second valve means and a temperature sensing element in heat transfer relation with said engine for operating the second valve means in response to temperature of the engine, said second valve means controlling fluid flow between the pressure receiving tank and the fluid actuator motor and unloading means.

3. In a gas compressor system including gas compressor means for compressing a gas such as air, a gas receiving chamber supplied with compressed gas from said compressor means, said compressor means including unloading means for preventing compression of gas, drive means for driving said gas compressor means, and control means for moving said drive means to an idling position wherein it operates at a certain low speed and for moving said unloading means to prevent gas compression in response to a first predetermined pressure in said receiving tank, and wherein said control means further includes means for moving said drive means to a full speed position and for simultaneously restoring said unloading means to permit compression of gas by said compressor means in response to a second predetermined pressure in said receiving tank lower than said first predetermined pressure, and wherein said drive means includes an internal combustion engine including a carburetor having a throttle shaft for moving the carburetor between idling and full speed positions, said control means being operatively connected to said throttle shaft to operate the same between idling and full speed positions in response to pressure in said receiving tank, and wherein said gas compressor means is an air compressor having an air inlet manifold for supplying said air compressor cylinders with air, said manifold being connected to said carburetor for diverting some of the air away from the air compressor cylinders to reduce temperature in said cylinders.

4. In combination with a carburetor for an internal combustion engine, the carburetor including a rotatable throttle shaft for operating the carburetor and a throttle lever fixed to said shaft to rotate the same upon pivotal movement of the lever; means for actuating and controlling the lever comprising, a fluid motor, interconnecting means including a reciprocable rod interconnecting said fluid motor and said lever to pivot the lever, a fixed support, a stop movably mounted on

said fixed support for movement towards or away from said rod to adjust the distance between said rod and said stop, said stop being engageable by said rod to limit movement of said rod in one direction, and wherein there is further included resilient means on said stop for absorbing shocks from said rod.

5. A combination defined in claim 4 wherein there is further included second stop means engageable with portions of the lever to limit movement of the lever in the opposite direction.

6. The combination defined in claim 4 wherein said lever is located on one side of said rod and there is further included a pin interconnecting said lever adjacent the free end thereof and one side of said rod.

7. The combination defined in claim 4 wherein said resilient means is a bumper on the stop engageable with said rod.

8. A combination defined in claim 4 wherein said fluid motor has an actuating stem and wherein there is further included adjustable coupling means interconnecting said actuating stem and said rod and being adjustable to vary the distance between the rod and the fluid motor.

9. A combination defined in claim 8 wherein said stop has a plurality of threads and wherein said fixed support has a threaded passage receiving said stop with the threads interengaged for adjusting said stop relative to the fixed support.

10. The combination defined in claim 4 further including an international combustion engine supplied with fuel by said carburetor, an air compressor driven by said engine, an air receiving tank supplied with compressed air by said air compressor, said fluid motor being connected to said air receiving tank to be operated by air therefrom when the pressure in said tank reaches a predetermined value to move the carburetor shaft into an idling position for operating the engine at an idling speed.

15. The combination defined in claim 10 further including spring means for moving said fluid actuator motor and said rod in an opposite direction for moving the throttle into a full speed position for compressing air when the pressure in said receiving tank reaches a second predetermined value lower than said first value.
